UNITED STATES PATENT OFFICE.

WILLIAM S. HATHEWAY, OF DEANSVILLE, NEW YORK.

PROCESS OF AND APPARATUS FOR DEODORIZING ORGANIC SUBSTANCES.

SPECIFICATION forming part of Letters Patent No. 278,955, dated June 5, 1883.

Application filed July 5, 1882. (No model.)

To all whom it may concern:

Be it known that I, WILLIAM S. HATHEWAY, a citizen of the United States, residing at Deansville, in the county of Oneida and State of New York, have invented a new and useful Atmospheric Deodorizer, of which the following is a specification.

The present invention relates to a method and apparatus for deodorizing or purifying organic bodies, such as tainted meats, rancid butter, and other analogous objects.

The invention consists in immersing the object to be deodorized in water or other liquid and forcing atmospheric air through the same. When impure bodies are immersed in pure water and air is forced into the same by a bellows, pump, or other apparatus, the oxygen of the air serves to attack any impurities or poisons more actively than under ordinary conditions. I also propose to cool the air, whereby a greater amount of oxygen is held in the water, thereby insuring a more speedy action of the oxygen upon the impure bodies immersed in the water. The rationale of my process seems to be that the water becomes a conductor for the oxygen, and holds the latter distributed therethrough, so as to cause a speedy attack of the oxygen upon the objects immersed in the water for purification.

In the accompanying drawings, Figure 1 is a vertical section of an apparatus by which my invention may be carried into effect. Fig. 2 is a section on the line 2 2, Fig. 1. Fig. 3 is a section of a small bellows for use by hand.

Referring to Fig. 1, A A represent parts of a suitable frame or table, and B B bellows mounted thereon, connected by operating-rods C C with a beam, D, by means of which a movement is imparted to the said bellows. If the bellows are to be operated by direct pressure applied to their upper surfaces alternately, cords may be substituted for the rods C C. If, on the other hand, the forcing as well as the filling stroke is applied to the bellows by means of the beam D, rigid rods will be requisite, or some indirect connection by which the forcing-pressure will be applied. The form of bellows here shown in Fig. 1 is well adapted for working with the feet with slight labor, the operator standing with one foot on each bel-

lows B B', bearing on them alternately, and allowing each to rise while the other is depressed.

In cases where it is desirable to reduce the temperature of the air used in the apparatus below that of the atmosphere, a suitable ice-chest is employed, as shown at E, surrounded by an air-chamber, F, communicating with the ice-chest E through a suitable grating, G, on which the ice rests.

A supply-pipe, H, conducts from the air-chamber F to branches h h', communicating with the bellows B B', so that the said bellows will be filled at each stroke with air forced by atmospheric pressure through the ice-chest E and chamber F, and the cold air will at the next stroke be driven through the discharge-pipe I and nozzle I' into the deodorizing-tank J, below the surface of the water or other liquid therein. The nozzle I' delivers the air underneath a perforated false bottom, K, by which it is distributed over the area of the tank.

A removable screen or grating, L, is employed for the purpose of confining meat, butter, or any other article to be treated under the surface of the liquid in the tank.

In proceeding on a small scale, a hand-bellows, B', such as is represented in Fig. 3, may be used with similar effect. M in Fig. 1 represents a siphon-pipe for discharging ice-water from the bottom of the tank. N represents a body of cotton or other filtering material for straining the incoming air.

By means of my apparatus I am enabled to purify impure bodies or substances immersed therein, such as rancid butter, or butter improperly salted, or meats that are in a tainted state, or any oleaginous bodies that are impure or possessed of an impure or undesirable odor, such solid bodies being confined below the surface of the liquid in the tank J by a screen, L, or other means. By means of my apparatus all such impurities are at once removed, fermentation can at once be stopped, and mold or musty growth can at once be arrested and removed, together with accumulated acids or gases arising therefrom.

The ice-chest may be dispensed with where it is not desirable to cool the material under treatment.

For applying my process on a small scale, I

prefer to use a simple cylindrical bellows, such as illustrated in Fig. 3. B represents the bellows, H the induction-pipe, and I a flexible discharge-pipe connected with a perforated glass nozzle, I', by which air can be carried into the bath containing the substances to be deodorized, a sieve or strainer filled with filter-cotton being employed, as before, so that the air shall be thoroughly strained before entering the bellows.

I am aware that it is not new in the process of cheese-making to cool the milk and deprive it of animal odors by forcing air through the same; also, that air has been forced through cheese for drying and purifying the same while being worked and drained of whey.

Having thus described my invention, the following is what I claim as new therein and desire to secure by Letters Patent:

1. The process of deodorizing organic substances, consisting in immersing the same in a body of water or other liquid and forcing atmospheric air through the liquid containing said organic substances, as and for the purpose set forth. 20

2. An apparatus for deodorizing organic substances, consisting of the liquid-tank J, perforated plates K L, air-inlet nozzle I', passing through said plates, air-pipe I, and an air-forcing apparatus connected with said pipe, as 25 and for the purpose set forth. 30

WILLIAM S. HATHEWAY.
